J. CUSICK.

RAIL JOINT.

APPLICATION FILED MAR. 24, 1911.

993,153.

Patented May 23, 1911

FIG. 1

UNITED STATES PATENT OFFICE.

JOHN CUSICK, OF SHARON, PENNSYLVANIA.

RAIL-JOINT.

993,153.

Specification of Letters Patent. Patented May 23, 1911.

Application filed March 24, 1911. Serial No. 616,677.

To all whom it may concern:

Be it known that I, JOHN CUSICK, a citizen of the United States of America, residing at No. 18 New Castle avenue, Sharon, 5 in the county of Mercer and State of Pennsylvania, have invented certain new and useful Improvements in Rail-Joints, of which the following is a specification, reference being had therein to the accompanying 10 drawing.

This invention relates to rail joints and to certain new and useful improvements in my Patent No. 985,572 granted February 28th, 1911.

15 Besides having the same objects in view as disclosed in my prior patent above referred to, the present invention aims to provide a rail joint having parts more quickly assembled and installed, the joint being 20 constructed whereby one of the rails can be detached without necessarily disturbing the other rail.

With the above and other objects in view the invention resides in the novel construction, combination and arrangement of parts 25 to be hereinafter specifically described and then claimed.

In the drawing:—Figure 1 is a perspective view of the rail joint. Figs. 2 and 3 are 30 perspective views of the members of the rail joint. Fig. 4 is a side elevation of the rail joint, partly broken away and partly in section, and Fig. 5 is a cross sectional view of the same.

35 The reference numeral 1 denotes a splice bar constituting one of the members of a rail joint and this splice bar, intermediate the ends thereof, is provided with an enlargement 2 which in cross section corresponds to the cross section of a rail, with the 40 following exceptions: The outer side of the head of the enlargement 2 is provided with an over-hanging lip 3 and the base 4 of the enlargement with a lateral extension 5.

45 The rails to be held are designated 6 and the ends of said rails are adapted to abut against the ends of the enlargement 2, said

rails resting upon ties or sleepers 7 and supporting the splice bar 1 upon the inner sides thereof with the enlargement 2 between the 50 ends of said rails.

The reference numeral 8 denotes an outer splice bar adapted to engage the outer sides of the rail 6, said splice bar having the ends thereof provided with lateral flanges 9 and 10 having spike recesses 11 for spikes 12. The splice bar 8 has the upper and lower edges thereof cut away, as at 13 and 14 to provide clearance for the over-hanging lip 3 and the lateral extension 5 when the splice bar 8 is placed in engagement with the rail 6. After the splice bar 8 is in position it can be driven in one direction to move the cut away portions 13 and 14 out of alignment with the lip 3 and the extension 5. As 65 the splice bar is shifted, a tapering rib 15 carried by the upper edge of the bar moves into engagement with the inner side of the over-hanging lip 3, and thereby holds the upper edges of the bar in engagement with 70 the rails. After having been driven into position the spikes 12 can be mounted in the tie and an outward extending lug 16 carried by the flange 10 prevents a rearward movement of the bar 8.

75 It is thought that the manner of assembling a rail joint will be apparent without further description and while in the drawing there is illustrated a preferred embodiment of the invention, it is to be understood 80 that the structural elements are susceptible to such changes as fall within the scope of the appended claim.

What I claim is:—

In a rail joint, the combination with ties 85 and rails adapted to be supported by said ties, of a splice bar engaging the inner sides of said rails, an enlargement carried by the inner side of said splice bar and adapted to fit between the ends of said rails, an over- 90 hanging lip carried by the outer side of said enlargement, a lateral extension carried by the outer side of said enlargement, an outer splice bar adapted to engage the

outer sides of said rails, said splice bar having the upper and lower edges thereof cut away to provide clearance for said lip and said lateral extension, a tapering rib carried by the upper edge of said splice bar and adapted to engage the inner side of said lip when said bar is shifted, and means including spikes adapted to hold said outer splice

bar in engagement with said rails, substantially as described. 10

In testimony whereof I affix my signature in the presence of two witnesses.

JOHN CUSICK.

Witnesses:

C. T. HOOD,
MAX H. SROLOVITZ.
